UNITED STATES PATENT OFFICE

2,545,749

REFRIGERATOR CABINET STRUCTURE

Walter H. Pusch, Fort Worth, Tex.

Application March 1, 1948, Serial No. 12,215

7 Claims. (Cl. 62—89)

1

This invention relates to refrigeration units of the automatic type, particularly adapted for use in homes, and other domestic applications; its principal object residing in the provision of a commodious cabinet preferably having a circular inner wall whereby a rotative rack support behind a transparent sliding panel may be provided to afford ready accessibility to all parts of the storage space at any time, thus providing for storage of maximum quantities of products in a minimum amount of space without crowding and enabling the user to rotate the rack support and thus observe the contents of the cabinet with a minimum amount of effort while confining the refrigerating air behind the transparent panel.

It is an object of the invention to provide an especially designed refrigerating unit in which is embodied features of design affording a wider cooling range for certain products requiring exceptionally low temperatures; while providing ample storage space for products requiring lesser amounts of refrigeration; while providing still milder temperatures for such as the firming of butter; and minimizing the necessity for frequent defrosting by applying a gentler cold over a wider area for the food preservation chamber, and by avoiding imprisoning moisture on frozen coils, which generally has a deteriorating effect upon certain types of foods.

Another object of the invention is that of providing a structure which embodies features of design rendering it capable of being embodied in a variety of forms of construction by which the same may be applied to certain odd shaped storage spaces, as in corners, small closets, and combination kitchen units; and thus avoiding conventional designs of rectangular cabinets which must be set away from confining walls for proper circulation.

A still further object of the invention resides in the provision of a unique arrangement of removable storage racks capable of being vertically spaced as desired to provide a maximum of storage space within the cabinet with flexibility of arrangement adaptable to varying storage problems.

Yet another object of the invention resides in the provision of a special squeegee arrangement whereby the walls, including the top and bottom of the interior of the cabinet, may be kept free from condensate moisture as the rotative storage racks are operated, from time to time; such condensate to be drained to a central point where the condensate can be sponged out or drained.

Broadly, the invention contemplates the pro-

2

vision of a refrigeration unit which provides for the maximum amount of effective storage in a minimum amount of space so that the cabinet in which the device is arranged may be designed to conformably fit into otherwise unusable spaces, such as odd shaped corners, and other similar recesses not ordinarily considered desirable for the arrangement of refrigerating units; and so that storage may be reviewed and items selected without undue loss of cold.

While the foregoing objects are paramount, other and lesser objects will become manifest as the description proceeds, taken in connection with the appended drawings wherein:

15 Figure 1 is a transverse cross-sectional view illustrating the preferred form of the invention, taken on lines 1—1 of Figure 2, showing the circular outer walls and the conformable inner walls in which an annular space is provided for the circulation of the refrigerant, and illustrating the 20 circular arrangement of storage racks and the transparent inner front closure of the cabinet.

25 Figure 2 is a vertical cross-sectional view, taken on lines 2—2 of Figure 1, illustrating the freezing compartment in the top of the cabinet and showing the arrangement of rotative rack supporting means in the cabinet.

Figure 3 diagrammatically illustrates, in lateral section, the freezing compartment, and illustrates the arrangement therein of a set of freezing trays.

Figure 4 is a fragmentary vertical cross-sectional illustration of the butter compartment in the closure of the refrigerator cabinet, taken on lines 4—4 of Figure 1, showing the automatic temperature adjustment means for the said butter compartment.

Figure 5 is a fragmentary lateral cross-sectional view through the automatic ventilating device, taken on lines 5—5 of Figure 4.

Figure 6 is a perspective illustration of the rotatable rack support showing wipers arranged thereon for wiping the moisture from the top, bottom, and sides of the circular interior of the cabinet, and showing the turning ring for turning the rack while the inner transparent door of the cabinet is closed.

Figure 7 is a plan view of an arrangement of semi-circular racks adapted to be installed on the rack support shown in Figure 6.

Figure 8 is a fragmentary detailed cross-sectional illustration of the wall construction of the cabinet, illustrated in Figures 1 and 2, and fragmentarily showing the rack support shown in Figure 6.

Figure 9 is a fragmentary front elevational view, showing a portion cut away, of the transparent closure for the circular cabinet interiorly of the front door thereof, and illustrating a roller supporting the same in operation.

Figure 10 is a fragmentary perspective view of the locking means for each of the semi-circular rack members shown in Figure 7.

Figure 11 fragmentarily illustrates, in partial section taken on lines 11—11 of Figure 12, a plan view of one form of the exterior casing for the cabinet showing an insulated water container adapted to be cooled by the unit and having a dispensing spigot thereon.

Figure 12 is a fragmentary elevational illustration, showing portions cut away, of the water cooling device illustrated in Figure 11, the illustration being taken on lines 12—12 of Figure 11.

Figure 13 is a fragmentary side elevational view of the water cooling device embodied in the cabinet, showing a closure for the front of the device providing a tray when hinged downwardly, as shown in dotted lines in Figure 13.

Figure 14 is a front elevational view of one form of the cabinet in a single domestic unit, showing the front door, the automatic "butter conditioner" unit, and a water cooling compartment.

Figure 15 is a plan view of one form of the cabinet shown to be positioned in a corner of a room.

Figure 16 is another plan view of the invention adapted to arrangement in a corner by having the front door at right angles to one of the walls, and

Figure 17 illustrates another adaptation of the invention in a unique cabinet arrangement in which is embodied certain other useful features.

It is contemplated, therefore, that the invention in its preferred form be provided with a housing 10 of any desirable exterior shape, but having circular internal walls, as illustrated in Figure 1. In such an arrangement a greater effective storage area may be provided with maximum accessibility due to the fact that the invention includes a maximum flexibility of shelf arrangement made possible, as shown in Figure 6, by a plurality of vertical standards 11 which have widened portions 12 formed on their lower ends, having a plurality of sets of perforations 13 at spaced levels, to support grill types of racks 14 such as that illustrated in Figure 7, and due to the fact that the rotary rack supporting device as shown in Figure 6 may be rotated, to bring any and all food stored on the racks to the front for easy selection while the transparent inner door 25 still remains closed to prevent convection cold-loss while locating wanted items.

Conformable to the interior circular wall 15 of the housing 10 is preferably provided an exterior circular wall 16 spaced from the inner wall 15 to provide for insulation 17, as illustrated in Figures 1 and 2. Another inner wall 18 is arranged between the walls 15 and 16, forming a liquid-tight compartment between the wall 15 and the wall 18, within which is a serpentine conduit, or a coil 19 for the passage of refrigerant gases, the remaining space of the liquid-tight compartment being filled with a stable, non-corrosive, anti-freeze fluid or other liquid or solid cold-conducting material which will then conduct the concentrated cold of the refrigerant conduit 19 to the inner wall 15 in diffused and mild form, thus preventing the formation of frost on the chamber side of the inner wall 15 while yet cooling the

food chamber to proper proportions, as a large surface just above freezing will exert the same cooling effect as a very small surface considerably below freezing.

5 The hinged door 22 in the front of the housing 10 is of such thickness as to accommodate a chamber 23 having a storage compartment therein, presently to be described, and which is especially designed to receive small amounts of items, such as butter, maintaining this commodity at firm but spreadable consistency. A hinged door 24 is provided for the small firming compartment, providing accessibility to the latter without opening the primary door 22.

15 A transparent closure 25 for the opening in the front of the cabinet 10 is slidably arranged interiorly of the latter and is curved in transverse section conformable to the curvature of the interior wall 15 of the housing 10, as illustrated particularly in Figure 1. The closure 25 is adapted to slide horizontally in a segmental recess 26 formed in the interior wall 15 as access is desired to the interior of the housing 10. Meanwhile, by reason of the transparency of the closure 25, the contents of the cooling chamber can be observed without opening the closure 25 to allow cold air to escape and warm air to enter. A lamp 25' is provided for the illumination of the interior of the cabinet 10. It is desirable to afford a lamp having bacteria-inhibiting properties and capable of bathing the contents as the racks are rotated.

20 A suitably insulated top 27 and bottom 28 are provided for the housing 10, as shown in Figure 2, and a freezing compartment 29, preferably having a circular form, as illustrated in Figure 1, is arranged in the upper portion of the housing 10, as shown in Figure 2. The freezing compartment 29 is suitably insulated by insulating material 30 arranged between the refrigerant conduits 34 and outer walls 32 of the compartment 29 so that any cold loss to the main chamber may not be of such concentrated intensity as to cause frost formation in the main cooling chamber. Between the freezing compartment inner wall 29 and the freezing compartment insulation is a plurality of vertical passages 34, serpentine as required, for the passage of the refrigerant gas. A hinged closure 35 closes the opening into the freezing compartment 29, as illustrated in Figure 1.

25 Any arrangement of trays for the compartment 29 may be employed, but it is desirable that the vertical subdivision of the space be as shown in the trays 37, 38 and 39 in Figure 1, and diagrammatically illustrated in Figure 3. By reason of the fact that the freezing compartment 29 is substantially circular in form, as shown in Figures 1 and 3, it is necessary to form the trays in segments such as 37, 38 and 39, so that the central tray 37 is substantially rectangular in form, having one arcuately formed end, while the opposingly arranged trays 38 and 39 each have the form of a segment of a circle and are oppositely arranged, as in Figure 3. In this arrangement the central tray 37 must be removed from the compartment 29 before either of the trays 38 or 39 can be removed therefrom, as demonstrated in the diagrammatic illustration shown in Figure 3. Horizontally, the freezing chamber space may be divided into various tray levels, and spaces 36 may be left for loose storage of packaged frozen foods not requiring tray storage.

30 The rack support shown in Figure 6, and comprising the plurality of vertical standards 12, has a manual-turning ring 40 arranged about its top

and connected to the upper ends of the standards 12 while the latter are radially connected by horizontal bars 41 at whose intersection 42 centrally of the assembly is an integral pintle 43 projecting downwardly to engage a bearing 44 in the bottom 28 of the housing 10, as illustrated in Figure 2. Concentrically of the ring 40 at the top of the rack support is a bearing ring 45 having a race 46 formed circumferentially internally thereof for bearings 47 whose internal race 48 is arranged about the exterior wall 32 of the freezing compartment 29, as also shown in Figure 2. The rings 40 and 45 are rigidly connected and spaced by a plurality of spacers 49 secured at the top of each of the standards 12, in the manner illustrated in Figure 6.

It is desirable to arrange a semicircular wire tray 50 in the upper end of the rack support shown in Figure 6 to accommodate bottles, jars, and other articles not conveniently arrangeable upon shelves or racks. As the rack support is rotated by manually operating the ring 40 within the housing 10 any item within the latter and supported upon the rack can be brought before the opening over which the door 22 is arranged, the sliding closure 25 being pushed back into the recess 26, so that ready access may be had to the articles without disturbing other objects stored in the cabinet. This is also true of the wire shelves or racks 14 which may be arranged upon the standards 12, either in units, as shown in Figure 7, or in half units in a manner which will be presently described.

The food racks 14, illustrated in plan in Figure 7, are preferably provided in sections 51 and 52, each constituting a segment of a circle. The outer rims 53 of members 51 and 52 are formed with substantially V-shaped crimps 54 adapted to embrace the portions 12 of the standards 11 and integral pins 55 are formed in one side to enter the outer of a pair of apertures 13 of the portion 12 of the standards 11 in the other side to enter the innermost of a pair of apertures 13, and be supported by the latter. Hinged latching devices 56 are arranged on the member 54 to be pressed downwardly beside the standards 11 to secure the sections in place and prevent their being accidentally dislodged. A detail of this arrangement is illustrated in Figure 10. It is desirable to provide the racks 14 in sections in order that they may be properly placed within the circular interior of the cabinet 10 and also to provide an arrangement whereby only half shelves or racks can be provided, quadrantly arranged, if it is desired to accommodate articles of different height, such as mustard jars and water melons, and the like.

The sliding transparent door 25 is mounted, at its top and bottom, in channel guide members 57 and 58, respectively, and one or more rollers 59 is provided at the bottom of the door 25 to expedite its movement along the lower channel 58, as illustrated in Figures 8 and 9. This arrangement may be modified according to the individual requirement. The top channel guide member 57 is shown to be considerably below ceiling level of the cooling chamber, the manual turning ring 40 thus being accessible at the door of the cabinet for the purpose of turning the shelf support unit (Figure 6) in order to locate refrigerated item wanted before opening the transparent inner door 25. The ring 40 provides a closure for the space above the transparent closure or door 25 whose upper end, as apparent in Figures 2 and 8, is well below the top of the door 22.

Arranged longitudinally of at least one of the standards 11, and along the outer edge thereof, is a flexible strip 60, of rubber, or similar material, which is adapted to engage the inner surface of the inner circular wall 15 of the cabinet 10 in a squeegee action designed to constantly remove whatever condensate moisture may appear on the surface of the chamber. Each time the rack support is moved within the cabinet 10 the member 60 will function to wipe any moisture from the walls. Normal operation of the rack support will therefore keep the chamber walls clean and dry. Such a strip 60 may be provided longitudinally of one of the arms 49 connecting the rings 40 and 45 horizontally at the top of the rack support and is adapted to engage the ceiling, the underside of the top of the cabinet 10, and thus keep moisture from accumulating thereon in the same manner as on the inner walls.

In the compartment 67 in the chamber 23, formed in the door 22 of the cabinet 10, and illustrated in detail in Figures 4 and 5, a grilled rack 63' is provided upon which small quantities of such articles as butter, and the like, may be placed to receive sufficient but not excessive cooling. The compartment 67 is ventilated through a series of vertical slots 64 arranged on each side of the compartment and closable by a series of spaced closures 65 as the closure mechanism is slidably operated through the medium of an automatic thermal control apparatus 66. A slide 68 is arranged in a chamber below the rack 63', as illustrated in Figure 4, and moves horizontally sufficiently to open or close the vents or slots 64 in one wall of the chamber so as to alternately close the opening on one side while opening the same on the opposite side, admitting air from the atmosphere outside of the cabinet 10 in one operation while excluding cold air from the interior of the cabinet 10, and conversely, when the temperature is sufficiently high in the compartment 67 to open the slots 64 interiorly of the cabinet 10 and admit cold air to the compartment 67. The thermal control unit 66, of course, is caused to function by the variations in temperature, maintaining the temperature within the compartment 67 at suitable values to properly preserve the product stored therein and prevent over-refrigeration or from moisture deterioration.

By reference to Figures 11, 12 and 13, it will be noted that, if desirable, a water reservoir 69 may be provided to maintain cold drinking water capable of being dispensed through a suitable spigot 70. The reservoir 69 may be arranged on either side of the door 22 of a cabinet 10, and, if desired, there may be a closure 71 covering the spigot and filler cap 72, which is hinged at a to the cabinet 10, as illustrated in Figure 13, and is capable of being lowered to a horizontal position, as in dotted lines in Figure 13, to provide a tray for glasses, or other articles. Such an arrangement, however, is capable of being modified in any manner best suited to the particular requirements.

It has already been stated that it is contemplated that the exterior housing of the cabinet 10 may be of any desired form, as in Figures 15 and 16, adapting the same to be fitted into odd corners and close off the same against the accumulation of dust and dirt behind the cabinet 10 and between the latter and the walls against which it is placed, its placement against a wall being facilitated by the round cross-section of

the operative unit, thus allowing plenty of circulation space between the operative unit and the usual rectangular housing for diffusion of heat of compression of the operating mechanism. An example of the exterior for the cabinet 10 is illustrated in Figure 14 which shows the door 22, the door 24 and the louvers 64-65 to the butter compartment 67, the optional outside drop shelf 71, the base 21 for the compressor or absorptive system necessary to produce cold, as well as the louvers transversely of the door or closure 22 for the circulation of air from the mechanism to dissipate the heat of compression or flame. Obviously this arrangement may be modified to suit any particular requirement.

Figure 17 illustrates another optional form of the invention, embodied in a cabinet which may contain a plurality of drawers 73, and the top of which may be used as a kitchen counter or work surface. As shown, two cylindrical cooling chamber units may be used together with the refrigerating mechanism mounted within the gridded enclosure 74 between the two food storage units. Both of these units can be run off of one refrigerant compressor mechanism, for efficiency the refrigerant being directed to the unit needing it by means of such mechanism as a solenoid shunt valve sealed within the line. One of the storage units in such arrangement could easily be stepped up to act as a frozen-foods storage unit; the inner "freezer" unit then might be omitted, or, retained, it would act as an intense cold "quick freeze" for transforming raw foods to frozen foods of the desired fine-ice-crystal structure. The arrangements illustrated in Figures 14 through 17 are illustrative of the many forms in which the cabinet 10 can be provided.

It is also contemplated that certain changes and modifications may be resorted to in the design and arrangement of the invention in other respects without departing from the spirit and intent of the invention or the scope of the appended claims.

What is claimed is:

1. In a refrigeration unit, the combination with a cabinet having a cylindrical interior wall and an opening for accessibility and a hinged door for said opening, a rotatable rack supporting frame operatively arranged in said housing, the said frame comprising a plurality of vertical standards connected at their upper ends by concentrically arranged circular frame members, the innermost of said frame members providing an upper bearing a central pivot pin arranged in the bottom of said support and connected to the said standards by horizontal radial arms and providing a lower pivot for said rack supporting frame, means formed in each of said standards for supporting racks in said frame, and a sliding transparent closure for said cabinet adapted to be operated independently of said door.

2. In a refrigeration unit, in combination with a cabinet having a cylindrical interior wall and a freezing chamber therein, a rotatable rack supporting frame arranged within said cabinet and conformable to said cylindrical wall and having means thereon for adjustably supporting circular food racks, a circular bearing forming a part of the top of said rack supporting frame, a circular frame member formed with the upper end of said support and providing means for manually rotating the same, and a pivot formed centrally of the bottom of said rack supporting frame, the said frame operatively embracing said freezing compartment.

3. In a refrigeration unit having a cabinet formed with a circular interior wall, in combination, a rotatable food rack supporting frame pivotally arranged in said cabinet, the said frame comprising a plurality of vertical standards, each having means thereon for adjustably attaching the rim of a food rack thereto, means comprising a circular bearing connecting the tops of said standards, horizontally arranged radial arms connecting the lower ends of said standards and a central pivot connected to said radial arms, a ring arranged concentrically of said circular bearing providing means for rotating said rack support, and flexible means arranged on one or more of said standards and said arms engageable with the inner walls and bottom of said cabinet and wiping the same in operation.

4. In a refrigeration unit, in combination, a cabinet formed with inner circular walls, the said walls formed with an annular closed chamber having cooling coils arranged therein, a circular freezing chamber formed concentrically of the upper portion of said cabinet, a rotatable rack supporting frame operatively arranged in said cabinet and having its upper end embracing the said freezing chamber, means comprising a ring forming a part of the upper end of said rack supporting frame for manually rotating the same, means carried by said rack support for wiping moisture from the inner walls of said cabinet when said rack supporting frame is rotated therein, a door for said chamber, and a butter cooler formed in said door and accessible exteriorly of said cabinet while said door is closed.

5. In an automatic refrigeration unit having a cabinet and a circular inner wall therefor, a circular chamber formed in said inner wall, cooling coils arranged in said circular chamber, a circular freezing chamber arranged concentrically of said circular walls and in the top of said cabinet, a rack support frame rotatably arranged in said cabinet and embracing the said freezing chamber, inner and outer concentric ring members forming parts of the upper end of said cabinet, the inner ring member providing an upper bearing for said support and said outer ring member providing means for manually rotating said rack support frame, and means arranged on said rack support frame engaging and wiping said circular inner wall when said rack is rotated.

6. In a refrigeration unit, the combination with a cabinet having a cylindrical interior wall and an opening for accessibility, an outer door for said opening; a transparent inner sliding door conformable to said cylindrical interior beyond said outer door; a rotatable rack support operatively arranged in said housing, said support comprising a plurality of vertical standards having storage racks adjustably affixed thereon, upper and lower bearings on said support for free rotation thereof, a circular frame member connecting said vertical standards above the top of said transparent door providing means for rotating the said rack while the said transparent door is closed, and a butter cooling compartment in said outer door and accessible while said outer door is closed.

7. In an automatic refrigerator, in combination, an insulated cabinet having a cylindrical inner compartment having a freezing chamber in its upper portion conformable to the contour of said inner compartment, a rotatable rack supporting frame arranged in said compartment, the said rack supporting frame having a plu-

rality of radially spaced vertical members, a turning ring connecting said vertical members at their upper ends and a bearing ring for said frame arranged concentrically of said turning ring, a bearing pivot arranged centrally of the bottom of said frame, an opening in said cabinet having a hinged door, a slideable transparent inner door for said compartment adapted to be actuated independently of said hinged door, and a thermal-controlled conditioning chamber in 10 said hinged door having accessibility independently of the operation of said hinged door.
